UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

MOVABLE LINE-FINDER.

1,272,111.

Specification of Letters Patent.

Patented July 9, 1918.

Application filed May 27, 1915. Serial No. 30,715.

To all whom it may concern:

Be it known that I, ALVAH C. ROEBUCK, a citizen of the United States, residing at Woodstock, in the county of McHenry and State of Illinois, have invented certain new and useful Improvements in Movable Line-Finders, of which the following is a specification.

This invention relates to typewriters, and more particularly to that portion of a typewriter which is known as a line finder, and the principal object of the invention is to provide a shiftable or movable line finder which will travel with the platen and be in position with respect thereto in any shifted position of the platen.

Other objects will appear hereinafter.

In the drawings, Figure 1 is a side elevation with parts shown in section illustrating the invention as applied to those parts of a typewriter to which it appertains; Fig. 2 is a plan view of the line finder taken on a line just below the carriage frame, Fig. 3 is a front view, and Fig. 4 is a perspective of the finder proper.

Non-shiftable line finders are in common use but are objectionable for the reason that there is no line finder when the platen is shifted, as for example, when it is desired to write a line of capital letters, and also when the writing comes near to the bottom of the sheet, and especially on the last one or two lines, when bringing the platen to normal position after it has been shifted to print capitals, the edge of the paper having been shifted beyond the line finder, the paper catches on the line finder as the platen is returned to normal position. In the present invention these difficulties are overcome by making the line finder shiftable as the platen is shifted, by attaching it to one of the movable parts, such as the shift rail, by means of which the platen is shifted.

Referring more particularly to the drawings, the numeral 1 designates generally the frame or top plate of a typewriter machine to which the parts are secured and by which they are supported. Secured to the frame 1 are rails 2 and a carriage 3 has rails 4 with which the carriage is slid able in the well known manner. A sub-carriage 5 is shiftably mounted in the carriage 3 and supports a rotatable platen 6. A wheel bracket 7 is secured to the sub-carriage frame and supports a wheel 8 at its lower end.

The carriage shift frame comprises a rock shaft 9 pivotally mounted in the typewriter frame, and a shift rail 10 is connected to the rock shaft by frame parts 11. It is understood, of course, that the carriage shift frame is rocked by means of a key located in the keyboard of the typewriter and shiftable thereby for upper case writing, it being unnecessary to show this operating connection in the present exemplification of the invention.

In front of and below the platen is a type bar segment 12 in which the type bars 13 are pivoted, and at the upper end of the segment is a type bar guide 14. Between the rear of the segment 12 and one of the frame parts 1, as shown in Fig. 1, is a space in which is a ribbon vibrator 15 and a movable line finder 16. The ribbon vibrator is connected to a lever 17 which is pivoted to the carriage shift frame and oscillated in a well known manner by the action of the type bars, the degree of oscillation of the vibrator being varied in accordance with the position of the platen since the lever 17 is pivoted to the carriage shift frame.

Connected to the bottom of the front frame part 1, as shown in Fig. 1, is a bracket 18 having arms spaced apart for supporting a shaft 19. Mounted on the shaft is a bell 85 crank having arms 20 and 21, the latter of which is connected by means of a link 22 with a bracket 23 fixed on one of the frame parts 11 of the carriage shift frame.

The shiftable line finder consists of a single piece of material having upper extremities 24 disposed at the sides of the type bar guide 14, graduated at their upper edges and bent slightly at the extremity so that they bear against the platen 6 at the printing line. At the lower end of the line finder it is formed at the sides with ears 25 to which arms 20 of the bell crank are connected. Intermediate the ears 25 is a spring tongue 26 which extends rearwardly and downwardly from the body of the line finder and is formed at the end with a boss 27 in which an adjusting screw 28 is threaded. This adjusting screw is adapted to bear against the shift rail 10 and the tongue being of spring material causes a slight tension to be exerted upon the upper extremities 24 of the line finder so that they bear resiliently against the platen 6. In operation the carriage shift frame is operated in the ordinary

90

100

105

110

manner by means of a key lever and the position of the line finder 16 is varied in accordance with the position of the shift frame and consequently the position of the platen 5 by means of its connection with the shift frame, so that in whatever position the platen may be the line finder will define the actual printing line. Since the line finder shifts with the platen there will be no tendency 10 of the paper, even when writing at the bottom thereof, to slip from its position on the platen because it engages with the line finder, for the shiftable line finder will tend to hold the bottom of the paper in position 15 against the platen and this will materially assist in writing a line at the bottom of a sheet by holding the paper in proper position and thereby preserving the alinement.

What I claim is:

20 1. In a typewriter, the combination of a shiftable platen, and a line finder separately pivoted in the typewriter frame having a connection which shifts the finder when the platen is shifted.

25 2. In a typewriter, the combination with a platen, of means to shift the platen, and a line finder separately mounted on the typewriter having a movable connection with the means and shiftable in accordance with the 30 movement of the platen.

3. In a typewriter, the combination with a shiftable platen, and a line finder pivoted in the typewriter frame and free from direct connection with the platen but having a portion 35 to engage the platen and define the printing line thereon and shiftable with the platen.

4. In a typewriter, the combination with a vertically shiftable platen, of a frame for 40 shifting the platen to its various positions, a line finder movably supported by the typewriter frame and having a portion to engage the platen, and a link connection between the frame and the line finder for shifting the line 45 finder in accordance with the shifting movement of the platen.

5. In a typewriter, the combination with a vertically shiftable platen, of a pivotally mounted shifting frame for the platen, a 50 vertically movable line finder separate from the frame, and a positive connection between the line finder and the pivotally mounted frame for oscillating the line finder in accordance with the shifting movement of the 55 platen.

6. In a typewriter, the combination with a shiftable platen, of means for shifting the platen, a line finder mounted in the typewriter frame independent of said means and 60 having an upper edge adapted to engage the platen, means to move the line finder in accordance with the movement of the platen, and a spring tending to press the upper edge of the line finder against the platen.

65 7. In a typewriter, the combination with a

vertically movable platen, of a pivoted shift rail for moving the platen, a pivoted vertically movable line finder independently mounted in the typewriter frame having an upper edge adapted to engage the platen, a 70 spring tongue tending to press the upper edge in engagement with the platen, and a positive connection between the line finder and the shift rail to oscillate the line finder in accordance with the vertical movement of 75 the platen.

8. In a typewriter, the combination with a platen, of a pivotally mounted shift rail for moving the platen vertically, a line finder having an upper edge adapted to engage the 80 platen, and a spring tongue at its lower edge, means forming a direct oscillating connection between the line finder and the shift rail, and an adjustable screw in the spring tongue adapted to bear against the shift rail 85 to press the upper edge of the line finder in engagement with the platen.

9. In a typewriter, a shiftable line finder consisting of a single piece of material formed with upper edges adapted to engage 90 the platen of the typewriter below the printing point, with ears for oscillating the line finder and with a depending spring tongue for engagement with a relatively fixed part to press the upper edge of the line finder in 95 engagement with the typewriter platen.

10. In a typewriter, the combination with a vertically movable platen, of a shift rail for moving the platen, a line finder vertically oscillatable at the front and below the platen 100 having a bent upper edge adapted to engage the platen below the printing line, a positive connection including a bell crank between the line finder and the shift rail, and a spring tongue having a boss at one end and screw-threaded in the boss for engaging the shift rail to press the upper end of the line finder 105 yieldingly against the platen.

11. In a typewriter, a frame, a platen shiftable in the frame, a shift rail for the platen, a line finder having an upper edge adapted to engage the platen just below the printing line and with projecting ears at the lower end thereof, a bracket supported by the frame, a shaft mounted in the bracket, a 110 bell crank secured to the shaft having connection with the ears of the line finder and with the shift rail for moving the line finder in accordance with the movement of the shift rail, and a spring tongue in connection with 115 the line finder adapted to engage a relatively fixed part to press the upper end of the line finder yieldingly against the platen.

12. In a typewriter, the combination with a vertically movable platen, of means for 120 shifting the platen to various vertical positions, a type bar guide, a line finder independently mounted in the typewriter frame reciprocable at the rear of the type bar guide with a forked upper end, the extremities of 125

which are at the sides of the type bar guide spaced therefrom and defining the printing line, and a link connection between the line finder and the said platen shifting means to move the line finder in accordance with the movement of the platen.

13. In a typewriter, the combination with a shiftable frame, of a rail for shifting the frame, a vertically movable line finder, means for separately mounting the line finder, and connecting means between the rail and the line finder for moving the latter in accordance with the movement of the platen.
14. In a typewriter, a shiftable platen, a rail for shifting the platen, a pivoted and vertically movable line finder, and a separate link connection between the shift rail and the

line finder for moving the latter in accordance with the movement of the platen. 20

15. In a typewriter, a shiftable platen, means for shifting the platen, a bell crank, a line finder pivoted to one arm of the bell crank and movable vertically thereby, and means connecting the other arm of the bell 25 crank and the means for shifting the platen so that the line finder will be moved in accordance with the movement of the platen.

In testimony whereof I have signed my name to this specification, in the presence of 30 two subscribing witnesses, on this 24th day of May A. D. 1915.
